UNITED STATES PATENT OFFICE.

LEWIS W. GERDON, OF MEADVILLE, PENNSYLVANIA, ASSIGNOR OF ONE-HALF TO EDWIN P. BARNES, OF CLEVELAND, OHIO.

MEANS FOR TYING WIRES TO INSULATORS, &c.

No. 878,520.

Specification of Letters Patent.

Patented Feb. 11, 1908.

Application filed October 14, 1907. Serial No. 397,375.

To all whom it may concern:

Be it known that I, LEWIS W. GERDON, a citizen of the United States of America, residing at Meadville, in the county of Crawford and State of Pennsylvania, have invented certain new and useful Improvements in Means for Tying Wires to Insulators, &c.; and I hereby declare the following to be a full, clear, and exact description 10 of the invention, such as will enable others skilled in the art to which it pertains to make and use the same.

This invention relates to new and useful improvements in line construction for telegraph, telephone and similar circuits.

The object of this invention is to provide a new tie for securing the line wire to the insulator which can be readily applied, which will accomplish a saving in time and material 20 over the tie now employed and which will effectually prevent the sagging or twisting of the wire at the point of support.

Generally speaking the invention may be defined as consisting of the features of construction described in the specification, pointed out in the claims and illustrated in the accompanying drawings, wherein

Figure 1 is a view showing an insulator, a portion of the line wire and a tie wire in the 30 first position. Fig. 2 is a similar view showing the tie wire with one loop around the insulator beneath the line wire. Figs. 3 and 4 are views from opposite sides showing the complete tie.

Again referring to the drawings 1 represents an insulator of the usual type which may be made of glass or other suitable material and has the usual groove 2 for receiving the line wire 3.

4 indicates the main portion of the tie wire and 4' the free end thereof. In forming the improved tie the tie wire is laid diagonally of the groove in the insulator and across the line wire so that the free end 4' thereof is 45 above the line wire and the main part of the tie wire 4 is below the line wire. The end 4' of the tie wire is held stationary and the rest of the wire is carried back around the groove in the insulator parallel with the bottom 50 ridge of said groove and is brought out at the front again underneath the line wire and is carried diagonally across the groove and over the line wire, and the tie wire so that the end thereof is above the line wire, and the tie 55 wire is then as shown in Fig. 2. Both ends

of the wire are then carried back around the insulator parallel with the upper ridge of the groove and are twisted together diametrically opposite the point where the line wire touches the insulator. It will therefore be 60 observed that where the line wire touches the insulator it is bound thereto by two thicknesses or strands of the tie wire and at each side of this point it is supported in the loops formed by the tie wire extending 65 around above and beneath the line wire. The line wire is therefore prevented from sagging or twisting as it would if it had but a single point of support as with the ties now generally used. Furthermore in making the 70 tie at present in use the ends of the tie wire are twisted around the line wire and this of course has to be done with a suitable tool and in twisting the tie wire around the line wire the tool comes in contact with the line wire 75 and not infrequently cuts or notches the line wire which causes the line wire to break at the point where it has been injured, when it has been in service for a time. In forming my improved tie the tool does not come in contact with the line wire at all as it is not necessary to use the tool except when the ends of 80 the tie wire are twisted together and this of course takes place at the opposite side of the insulator to that on which the line wire is 85 bound.

A further advantage resulting from the fact that the tie wire is not twisted around the line wire but is in reality one member of a clamp of which the insulator is the other 90 member is that in case the insulator becomes broken and falls off its support the tie wire will also fall off of the line wire of its own weight. This prevents a frequent cause of line trouble now met with for when the tie 95 wire remains attached to the line wire after the breaking of the insulator the projecting portion of the tie wire comes in contact with adjacent line wires causing entanglement of the line wires and short circuiting thereof. Furthermore the line repairer does not have 100 to expend any time in disengaging the tie from the line wire which operation, were it necessary, would also involve the danger of injuring the line wire as before explained. 105

What I claim is,—

1. The combination with an insulator and a line wire of a tie for binding the line wire to the insulator consisting of two members each of which completely encircles the insulator, 110

said members intersecting with each other and crossing the line wire at the point where the line wire is in contact with the insulator.

2. The combination with an insulator and a line wire of a tie for binding the line wire to the insulator consisting of two loops each of which completely encircles the insulator, said loops crossing each other and the line wire where the line wire is in contact with the insulator.

3. The combination with an insulator having a wire groove and a line wire adapted to lie in said groove of a tie wire bent around said insulator forming a loop around the bottom of the groove, the ends of said loop being crossed over said line wire and each other and bent around the insulator and twisted

together forming a second loop above the first-mentioned loop.

4. The combination with an insulator and a line wire of a tie for binding the line wire to the insulator consisting of a wire extending around the insulator below the line wire and crossing the line wire where it contacts with the insulator and extending again around the insulator above the line wire and having its ends united together.

In testimony whereof, I sign the foregoing specification, in the presence of two witnesses.

LEWIS W. GERDON.
